UNITED STATES PATENT OFFICE.

JOSEPH R. DOOLEY, OF MOBILE, ALABAMA.

RAILWAY-TIE.

1,073,030.

Specification of Letters Patent.

Patented Sept. 9, 1913.

Application filed March 15, 1913. Serial No. 754,413.

To all whom it may concern:

Be it known that I, JOSEPH R. DOOLEY, a citizen of the United States, residing at Mobile, in the county of Mobile and State of Alabama, have invented new and useful Improvements in Railway-Ties, of which the following is a specification.

The present invention relates to improvements in ties for railway rails and to means for securing the rails upon the ties.

In carrying out my invention I propose to construct a tie of reinforced concrete, steel or the like with means whereby the rail is effectively secured upon the tie and cushioned thereon so that the shock incident to the rolling stock passing over the rail is effectively absorbed, and danger of injury to the tie and rail reduced to a minimum if not entirely overcome.

20 I also propose to improve and simplify the construction of devices of this character so that the same will embody the desirable features of simplicity of construction, cheapness, ease of application, as well as thorough 25 effectiveness for the purpose for which it is designed.

As is well known in the art, ordinary reinforced plastic ties have met with little success for the reason that they have been 30 unable to withstand the shock and jar incident to the rolling stock passing thereover for the reason that the same are not, from their construction, permitted a sufficient amount of resiliency which will absorb the 35 said shock and jar. This is also true of the metallic ties. With the general construction of either plastic or metallic ties, the means for sustaining the rails upon the ties also have not been found effective.

40 In some instances the securing means are not only complicated, but require a great amount of time as well as a thorough acquaintance with each of the separate parts before the same can be properly applied 45 to the ties, and owing to the non-resiliency of the ties heretofore alluded to, the securing means have been found unreliable and easily broken or loosened from the tie and thus entirely lose their effectiveness.

50 It may therefore be considered the pri-

mary object of my invention to provide in combination with a metal or reinforced plastic tie, a novel rail fastening and shock absorbing means, which will hold the rail firmly under all conditions and at the same 55 time absorb all the shock transmitted to the rail by the heavy loaded cars as well as arranging and constructing the fastening means so that the same will at all times automatically adjust themselves to secure 60 engagement with the rails when the absorbing means have been worn or depressed.

With the above recited objects in view, and others which will be apparent as the nature of the improvement is more fully 65 understood, the invention resides in the construction, combination and operative arrangement of parts set forth in the following description and falling within the scope of the appended claims.

70 The essential features of the invention involved in carrying out the objects above referred to are necessarily susceptible of embodiment in various forms of construction without departing from the scope of the invention, but certain preferred and practical embodiments are exemplified by the accompanying drawings, in which:

Figure 1 is a perspective view of a rail tie constructed in accordance with the present invention, and illustrating a rail in locked position thereon, Fig. 2 is a central longitudinal sectional view through the same, Fig. 3 is a top plan view of the tie, the cushion and rail securing means being 80 removed, Fig. 4 is a perspective view of one of the rail clamps, and its co-acting hook bolt, and Fig. 5 is a perspective view of one 85 of the cushion members.

90 Referring now to the drawings in detail, the numeral 1 designates the tie. The tie, in the present instance, is constructed of reinforced concrete, but it may be here stated that it is to be understood that I am not to be limited to the material from which 95 the tie is formed, as the said tie may be made of metal, either solid or hollow, or of any other material which is found desirable. The tie 1 is preferably of the ordinary rectangular formation, and has its upper face 100

flat and horizontally straight. The tie adjacent its opposite ends is formed with a pair of spaced transversely arranged vertically extending ribs or flanges 2 and 3 respectively. These flanges are spaced a distance greater than the width of the webs of the base flanges of the rails R. The inner faces of each of the ribs or flanges 2 and 3 are inclined outwardly, as at 4, from the central portion 5 thereof, the said central portion being substantially rectangular and having its outer face arranged substantially in a plane parallel with the outer edges provided by the inclined walls 4. The face of the tie between the rectangular portions 5 of the flanges 2 and 3 is preferably depressed to provide a pocket 6, and embedded within the tie and straddling the longitudinal walls provided by the pocket 6, is a central staple 7 as well as staples 8, each of which being arranged a suitable distance away from the central staple and away from the outer face of the central portion 5 of the ribs or flanges 2 and 3. The end walls of the pocket 6 may be, and preferably are, curved toward the bottom wall of the said pocket, and the said end walls having their upper portions arranged in a plane with the inner faces of the members 5 of the ribs. By providing the ribs with the inclined faces or walls 4 it will be noted that I have provided the tie with substantially dove-tailed pockets that are disposed to the opposite sides of the depression or pocket 6, and these dove-tailed pockets or compartments are adapted to receive each a cushion member, in the nature of a block 9. The blocks 9 each has its opposite sides inclined from its inner face toward its outer face to co-incide with the inclined walls 4, and the inner faces of the blocks also abut with the angular or longitudinal walls of the projections or portions 5 of the ribs 2 and 3. By such an arrangement it will be noted that an outward movement of the blocks 9 from their respective compartment or pocket is effectively prevented, as is also an inward movement of either of said blocks. The blocks may be constructed of any desired or preferred material which embodies a sufficient amount of resiliency to absorb the shock to the rails R (which are adapted to rest upon the said blocks) incident to the rolling stock passing over the tie.

In order to effectively sustain the rails upon the cushion members and also to retain the said cushion members within their pockets against vertical movement, I provide clamps 10 and 11. These clamps are each of a similar formation having an inclined body 12 and an inturned lip 13. The bodies 12 are adapted to be arranged between the rods 8 and the vertical faces of the portions 5 of the ribs, while the angular

or inturned lips are adapted to overlie the base flanges of the rails R. Co-acting with the members 10 and 11 are hook bolts 14 and 15. These bolts have their hooked ends engaging with the opposite sides of the central rod 7, and their stems arranged at an angle and passing through suitable openings 16 provided in a flattened portion of each of the members 10 and 11 disposed between its lip 13 and its body 12. The threaded shanks of the bolts are adapted for the reception of securing nuts 17, and the said shanks directly underlie the base flanges of the rail, so that should the cushion blocks become worn and the rail exert its full weight upon the hook bolts, the same will force the lips 13 of the members 10 and 11 more tightly into engagement with the flanges of the rails, and thus it will be noted that the securing elements automatically adjust themselves to any wear upon the cushion blocks.

From the above description, taken in connection with the accompanying drawings, the simplicity of the device as well as the advantages thereof will, it is thought, be perfectly apparent to those skilled in the art to which such inventions appertain without further detailed description.

Having thus described the invention, what I claim is:

1. In a device of the class described, a rail tie having its upper face provided with spaced ribs, the inner central portions of which being substantially rectangular and the inner walls being inclined from the rectangular portion to the outer edges of the ribs, cushion blocks for the rails, said cushion blocks having angular edges which are adapted to engage with the angular walls of the ribs and to abut against the sides of the rectangular central portions of the ribs, rail clamps having inclined jaws which are adapted to contact with the inner faces of the central rectangular portions of the ribs, members loosely and removably connected with the tie and arranged at an angle thereto and adjustably connected with the clamps, and the said inclined members being disposed directly below the lower longitudinal edges of the base flange of the tie.

2. In a device for the purpose set forth, a rail tie having spaced ribs, the inner walls of which being inclined toward the center of said ribs, and the central portion of each of the ribs embodying a rectangular projecting member, the tie between the rectangular members being depressed, a central rod straddling the depression and secured within the tie, a staple arranged within the tie and disposed adjacent each of the central rectangular portions of the ribs, cushion members, rail supporting members having inclined sides engaging with the inclined

walls of the ribs and abutting with the central rectangular portion of the ribs, clamp members having their body portions disposed between the rods adjacent the central 5 portions of the ribs and the said central portions of the ribs, said clamps having angular rail engaging lips, hook bolts engaging the central bar of the tie and disposed at opposite angles to the tie and passing through openings in the oppositely ar- 10

ranged clamps, bolt members for the hooks, and the said hooks adapted to lie directly below the longitudinal edges of the base flanges of the rail.

In testimony whereof I affix my signature 15 in presence of two witnesses.

JOSEPH R. DOOLEY.
